CLAIM

The ornamental design for a instrument for measuring skin lesions, or similar article, as shown and described.

DESCRIPTION

FIG. 1 is a top plan view of an instrument for measuring skin lesions, or similar article showing my new design;

FIG. 2 is a bottom plan view;

FIG. 3 is a left side elevational view, the right side elevational view being a mirror image;

FIG. 4 is a rear elevational view;

FIG. 5 is a front elevational view;

FIG. 6 is a top plan view, with the calipers in an open position;

FIG. 7 is a top plan view of another embodiment of my new design of FIGS. 1-6, the bottom plan view being a mirror image; and

FIG. 8 is a left side elevational view, the right side being a mirror image thereof.
